RUNNING BOARD

Charles S. Johnston, Glencoe, Ill., assignor to
Transportation Specialties Co., Chicago, Ill., a
corporation of Illinois

Application July 1, 1944, Serial No. 543,164

3 Claims. (Cl. 105—457)

1

This invention relates to running boards and more particularly to sectional running boards for use on railroad cars and the like.

One of the objects of the invention is to provide a running board which is easy and inexpensive to fabricate and assemble and which provides a strong light weight construction.

Another object of the invention is to provide a running board in which the parts are held assembled by interfitting relatively together without requiring separate fastening means.

Still another object of the invention is to provide a running board in which a plurality of sections are connected together and to the car by simple inexpensive fastening means. In one preferred construction, flanges project beyond the ends of the sections and overlap with flanges on adjacent sections and are secured thereto and to the car by a single set of fastenings.

The above and other objects and advantages of the invention will be more readily apparent from the following description when read in connection with the accompanying drawings, in which—

Figure 1 is a partial plan view of a railway car having a running board embodying the invention;

Figure 2 is a partial section on the line 2—2 of Figure 1;

Figure 3 is an enlarged partial plan view of the running board;

Figure 4 is a section on the line 4—4 of Figure 2; and

Figure 5 is a partial enlarged section of an alternative joint.

The running board of the invention is illustrated in connection with a conventional freight car construction although it will be understood that it might be used in many different environments. As shown, the freight car top is formed by the usual roof sheets 10 connected together by vertical abutting flanges 11 covered by capping strips 12. At the end of the car the end sheet has a downwardly turned flange 13 connected to a car end sheet 14.

The running board is formed by a plurality of sections each section as shown, being of a length to span two roof sheets. Each section is formed by transverse supporting members 15 adjacent the ends and in the central part of the section. Each supporting member is in the form of an angle bracket having a horizontal flange and a vertical flange. If desired, transverse braces 16 may be provided between the supporting mem-

bers and which are in the form of vertical flat strips.

The tread surface of the running board is formed by a series of parallel longitudinally extending channel members 17 extending across the supporting members. The web portions of the channel members may be perforated as indicated at 18 to form a tread surface of the type more particularly described and claimed in the patent to Moorman No. 2,091,157.

In order to secure the channel members to the supports and transverse braces 16, the vertical flanges of the supports and the transverse braces are formed with pairs of slots 19 open at the top and with the slots of the pairs lying at an acute angle to each other. The sides of the channel members are normally parallel and are spaced apart a distance equal to the distance between the tops of the pairs of slots 19. To assemble the channel members on the supports the sides of the channel members are placed above the slots and are forced down into the slots until webs of the channel members rest on the upper edges of the vertical flanges of the supports and the upper edges of the braces 16. This operation bends the sides of the channel members out of parallel as indicated at 21 and securely locks the channel members to the supports and braces. It will be noted from Figure 3 that the sides of the channel members remain substantially parallel between the supports and braces. In this way, the channel members are securely fastened to the supports and braces without the necessity of any separate fastening means to form a rigid running board section.

At the outer sides of the running board the supports and braces terminate in right angle edges and the outermost channel members are formed with long flanges 22 adapted to overlie such edges. Preferably, the flanges 22 are fastened to the edges of the supports and braces by welding or the like, this welding being the only assembling operation required other than the placing of the channel members against the supports and braces and forcing the sides of the channel members into the slots 19.

The several sections are assembled into a completed running board on a railroad car or the like by providing brackets 23 secured to the flanges 11 and covers 12 by riveting, bolting or the like. The brackets have horizontally extending flanges which are adapted to underlie the horizontal flanges on the supports 15. The brackets and supports may be connected by a series of bolts 24 or like removable fastenings.

At the point where two running board sections connect as seen at the left of Figure 2, two brackets 23 may be provided each underlying one of the transverse supports on one of the running board sections so that the running board sections are connected together and to the car.

At the end of the car as seen at the right of Figure 2, an additional transverse support 25 may be provided carried beyond the end of the car by a bracket 26. The end sections are made longer than the central running board sections to project beyond the ends of the car so that when several cars are coupled together a substantially continuous running board is formed.

Instead of providing separate brackets 23 at the points where the running board sections connect, the running boards may be formed as shown in Figure 5 to be connected by a single bracket. In this construction, one of the transverse supports 15 is formed with a long horizontal flange 27 extending beyond the ends of the channel members 17 to overlie the horizontal flange 28 of a support on an adjacent section. The horizontal flanges 27 and 28 may be connected to each other and to the bracket 23 by a single set of fastenings 29. In using this construction, one transverse support adjacent the end of each section will be formed with an elongated horizontal flange 27 while the other support on the same section will have a shorter flange such as 28. In this way, the sections can be assembled and connected to a car without requiring any special mounting brackets on the car and by the use of a single set of fastenings.

While two embodiments of the invention have been shown and described in detail herein, it will be understood that these are illustrative only and are not intended as definitions of the scope of the invention, reference being had for this purpose to the appended claims.

What is claimed is:

1. A running board for railroad cars and the like comprising a series of transverse supports adapted to be secured to the car, the supports being formed with pairs of substantially straight slots extending downward from the top thereof with the slots of each pair lying at an angle to each other, and a series of channel members normally having straight parallel sides extending

across the supports with the sides of the channel members fitting into the pairs of slots and held out of parallel thereby adjacent the supports to secure the channel members to the supports.

2. A running board for railroad cars and the like comprising a series of transverse supports adapted to be secured to the car, the supports being formed with pairs of substantially straight slots extending downward from the top thereof with the slots of each pair lying at an angle to each other, each of the slots lying at an angle other than a right angle to the upper edges of the supports, and a series of channel members normally having straight parallel sides extending across the supports with their webs resting on the upper edges of the supports and their sides fitting into the pairs of slots and bent out of parallel thereby adjacent the supports.

3. In a sectional running board of the type including a series of sections to be connected end to end, a section comprising transverse supports adjacent the ends of the section, the supports having vertically extending portions and horizontally extending portions, the vertically extending portions being formed with pairs of substantially straight slots open at the top with the slots of each pair lying at an angle to each other, and a series of channel members normally having straight parallel sides extending longitudinally of the section with their sides fitting into the slots and held out of parallel thereby adjacent the supports, one of the horizontally extending portions projecting beyond the ends of the channel members to overlie and connect to a horizontal portion on an adjacent section.

CHARLES S. JOHNSTON.
